UNITED STATES PATENT OFFICE.

JOHN M. SCHUH, OF CINCINNATI, OHIO.

HARNESS ATTACHMENT.

1,120,854.

Specification of Letters Patent.

Patented Dec. 15, 1914.

Application filed February 13, 1913. Serial No. 748,068.

To all whom it may concern:

Be it known that I, JOHN M. SCHUH, a citizen of the United States, and a resident of the city of Cincinnati, in the county 5 of Hamilton and State of Ohio, have invented certain new and useful Improvements in Harness Attachments, of which the following is a full, clear, and exact description, reference being had to the accompanying drawings, forming a part of this specification.

The object of my invention is to provide a buckle which may be firmly and securely attached without the use of rivets or expensive and difficult sewing, and may be removed at will, and I do this by that certain arrangement and construction of parts to be hereinafter specifically pointed out and claimed.

20 In the drawings, Figure 1 is a side elevation of a spring line end billet showing my improved buckle and attachment. Fig. 2 is a top plan view of the same, partially broken away, with one of the flexible strips 15 out of attachment. Fig. 3 is a top plan view of a crown piece, showing the buckle and one flexible strip removed. Fig. 4 is a perspective view of said buckle. Fig. 5 is a perspective view of one of the flexible 30 strips of said crown piece. Fig. 6 is a longitudinal section of a crown piece showing my improved buckle. Fig. 7 is a top plan view of the same, showing the over-check 35 loop in place, in the loops formed by said strips.

I am aware that a flat buckle having a base plate, two end arches and a central upwardly extending tongue or pin is old in the saddler's art, but there has been no means 40 of attaching such buckles, except by use of rivets or other unsightly means.

The buckle is not claimed by me as new in itself independent of its connections, nor does it comprise the essential novelty of my 45 invention, which is a buckle attached as shown in the drawings, leaving a smooth inner surface of the harness for contact with the animal without the necessity of using pads or other guards.

50 The buckle proper, as shown in Fig. 4, is formed of the base plate 1, the arches 2, 2, at each end of the plate, and the tongue or pin 3 upwardly extending from the center of the plate. For attaching this buckle I 55 provide the following means. In the strap 4, formed of two layers of leather, 5, 6, as

is customary in the saddler's art, are inserted two thongs or flexible strips 7, 7. These strips have each end portions 8, 8, wider than the body of the strips (Fig. 2). 60 Slots 9, 9, are cut in the top layer 6 of the strap as shown in the line in Figs. 1 and 2, of sufficient width to accommodate the narrow portion of the tongues, and spaced apart to admit of placing a buckle between 65 them.

In making up the harness, the strips 7, 7, are inserted between the layers before they are stitched together, with the end portions 8, 8, inside the layers and the narrower portion drawn through the slots 9, 9, in the upper layer 6,—the ends lying in opposed relation to each other. The buckle is then attached as follows. After the layers have been sewed together, the buckle is placed 75 along the strap with its respective ends opposite the slots 9, 9. The flexible strips 7 are then brought over the edge of the base plate 1 and under the arches 2. The eyes 10 are provided on the strips, spaced so as 80 to register with the pin or tongue 3, and after drawing the strips through the arches as aforesaid, they are attached to the tongue 3, one strip over the other, by the insertion of the same through the said eyes. The 85 buckle is then securely attached to the strap; and for utilizing it, under ordinary circumstances, the strap end or billet 11 to be buckled is passed under either arch, and fastened on the tongue 3 in the same manner 90 in which the flexible strips are attached.

For purposes of clearness, the other use of my buckle as shown in Figs. 3 to 7 will be described with different indicating numerals, although it will be understood that 95 the novel features are the same in these latter figures as in the ones above referred to.

I do not desire to be limited to any specific use of my improvement, by thus arbitrarily selecting two of the many uses to 100 which it may be put, but am using these selections for the purpose of illustration. It will be noted that the flexible strips are in the second instance brought out from the "set in" position between the layers at both 105 ends and both ends attached to the buckle.

The crown piece 12 is provided with the crown piece layer 13, said layer having slots 14, 14, spaced apart to receive the buckle between them. It is also provided with slots 110 15, 15, located outside of the slots 14, 14. The flexible strips 16 are provided, having

eyes 17, 17, at either end. In connection with the crown piece an over-check 18 is used, having a split 19. In making up the bridle, then, the flexible strips are located 5 between the layers of the crown piece, preferably before stitching them together, and their ends drawn through the slots 14 and 15. The buckle is then set between the slots 14, 14, and the inner ends 18 of each strip 10 fastened to the buckle as detailed in the first example. The over-check split is then placed in position over the crown piece, as shown in Fig. 7, and the outer ends 19 of the strips bent over the split portions and fastened 15 to the buckle as above. By this means, my new buckle attachment is utilized to provide guides or loops for an over-check without the necessity of sewing separate strips into the leather for each one of the lower 20 and upper attachments; and if it is desired to omit the over-check, then it will be possible to remove the buckle and guides, which is impossible in any bridles now on the market.

25 The advantages of my improvement are now obvious, consisting in removability, firmness of attachment, smoothness of inner surface of the harness, and inexpensiveness of operations necessary for attachment.

30 In the over-check feature, removability is of great importance, and it will be further noted that in case of breakage of the flexible strips in this structure, a new strip may 35 easily be inserted between the layers without resorting to the repair shop.

Having thus described my invention, what I claim as new and desire to secure by Letters Patent, is:—

40 1. In combination with a single strap of harness, a buckle having a base portion, and means for mounting the same on the strap

comprising a plurality of flexible strips set into the harness strap, in opposed relation to each other and spaced apart substantially the length of the base of the buckle, and 45 said strips provided with means of attachment to the buckle.

2. In combination with a single strap of harness, a buckle having a base portion, and means for mounting the same on the strap 50 comprising a plurality of flexible strips sewed into the strap and spaced apart substantially the length of the base of the buckle, said strips provided with means for attachment to the buckle. 55

3. In combination with a single strap of harness, a buckle having a base portion and a tongue and a plurality of flexible strips secured to the strap and spaced apart substantially the length of the base of the 60 buckle, and provided with eyes for impaling them on the tongue.

4. In combination with a single strap of harness, a buckle having a base portion and a tongue and a plurality of flexible strips 65 secured to the strap and spaced apart substantially the length of the base of the buckle, in opposed relation to each other, and provided with eyes for impaling them on the tongue. 70

5. In combination with a single layered strap of harness, a buckle having a base portion and a tongue and a plurality of flexible strips set between the layers of the harness 75 spaced apart substantially the length of the base of the buckle and extending therefrom in opposed relation to each other.

JOHN M. SCHUH.
